UNITED STATES PATENT OFFICE.

STANISLAW YAPCZENSKI, OF CHROME, NEW JERSEY.

DESIGN FOR A POCKET ARTICLE.

47,778.

Specification for Design.

Patented Aug. 31, 1915.

Application filed March 11, 1915. Serial No. 13,750. Term of patent 7 years.

To all whom it may concern:

Be it known that I, STANISLAW YAPCZENSKI, a citizen of the United States of America, residing at Chrome, in the county of Middlesex and State of New Jersey, have invented a new, original, and ornamental Design for a Pocket Article, of which the following is a specification, reference being had to the accompanying drawing, forming part thereof.

The figure is a side view of a pocket article, showing my new design.

I claim:

The ornamental design for a pocket article, as shown.

STANISLAW YAPCZENSKI.

Witnesses:

FELIKE SZYMBORSKI,
JOSEPH DZUDORF.
